(57) **CLAIM**

The ornamental design for an electric backpack sprayer tank, as shown and described.

DESCRIPTION

FIG. 1 is a perspective view of an electric backpack sprayer tank;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan elevation view thereof; and,

FIG. 7 is a bottom plan view thereof.

The broken lines in FIGS. 1-7 showing a battery module, pump arm, and wand hose connector are for the purposes of illustrating portions of the electric backpack sprayer tank that form no part of the claimed design.

1 Claim, 7 Drawing Sheets
